UNITED STATES PATENT OFFICE.

PAUL C. HAAN, OF NEW BRUNSWICK, NEW JERSEY, ASSIGNOR TO JAMES DONALD PICKARD, OF EAST ORANGE, NEW JERSEY.

APPARATUS FOR CARBONATING LIQUIDS.

No. 813,883.

Specification of Letters Patent.

Patented Feb. 27, 1906.

Application filed November 4, 1904. Serial No. 291,361.

To all whom it may concern:

Be it known that I, PAUL CLEMENS HAAN, a citizen of the United States, and a resident of the city of New Brunswick, county of Middlesex, State of New Jersey, have invented 5 certain new and useful Improvements in Apparatus for Carbonating Liquids, of which the following is a specification.

The object of my invention is to form a 10 mixture of carbonic-acid gas with liquids under pressure; and it consists in certain details simplifying construction.

In the accompanying drawings, which form 15 part of this specification, Figure 1 is a vertical section showing my invention. Fig. 2 is a plan view of a single convolution of gas-supply pipe with one deflecting-plate attached thereto.

The same reference characters indicate the 20 same parts throughout.

The receptacle, as shown at A, is to contain the mixed liquid and gas. The tank, as 25 shown at B, is to contain compressed carbonic-acid gas. A liquid-inlet, as shown at C, is made so that it may be carried upon or may be part of float D. A casing is made as at E F, of which the upper part E is designed to contain porous filtering material and the lower part F to hold superimposed 30 corrugated deflecting-plates. At the lower part of receptacle A there is furnished an inlet for gas consisting of a pipe coiled upwardly and perforated, as shown at G, above which is a finely-perforated distributing-diaphragm, as shown at H. An external gage I 35 may be employed to denote the minimum height of liquid in A. Spiral deflecting-plates K are connected with the coiled inlet-pipe G and may be made of one continuous spiral 40 plate or may consist of several separate sections forming a spiral conforming to the spiral of pipe G.

L is the liquid-supply pipe; M, the gas-supply pipe; N, the gas-control valve.

O P are valves respectively controlling liquid and gas pressure indicated upon gages R, 45 which consist of two ordinary gages contained in a single case, each having an index upon the face of the case.

S is safety gas-valve, T liquid-filter, and U draft-pipe.

The operation is as follows: Liquid being supplied under pressure through pipe L and filter T is distributed in a spray by inlet C on float D within the receptacle A. Gas being 55 supplied under pressure from tank B passes through pipe M to perforated coil G and is deflected by spiral plates K. The gas passing upwardly is distributed by the perforated diaphragm H and the deflecting-plates F. It 60 is then caught and further caused to mix with the liquid by the porous filtering material E. The float D governs the height of the liquid in A in the ordinary manner. The liquid-inlet C, which is carried upon float D, is 65 adapted to spurt upwardly through an atmosphere of gas, thus causing the liquid and gas to be mixed. The carbonated liquid may be drawn off through the pipe U.

What I claim, and desire to secure by Letters Patent of the United States, is—

1. A liquid-carbonating apparatus, comprising a containing-tank for liquid and gas under pressure; a liquid-inlet-governing float, arranged to carry a nozzle adapted to spray 75 the liquid upwardly through an atmosphere of compressed gas, to form a combination of the liquid and the gas.

2. In a liquid-carbonating apparatus comprising a tank for liquid and gas under pressure, an upwardly-coiled perforated gas-inlet pipe, having attached spiral deflecting-plates, and a superimposed perforated distributing-diaphragm to diffuse compressed gas through a body of liquid held in a receptacle. 85

3. In a liquid-carbonating apparatus comprising a tank for liquid and gas under pressure, a gas distributing and diffusing inlet comprising a vertical perforated coil with spiral deflecting-plates attached thereto, having a superimposed casing containing a series of corrugated deflecting-plates surmounted by a stratum of porous material, to cause the union of liquid and gas held in the containing-receptacle, by bringing them into intimate 90 contact under pressure. 95

Signed in the presence of two subscribing witnesses.

PAUL C. HAAN.
